MIXING APPARATUS

Wendell W. Jones, Aspinwall, Pa., assignor to
 Armstrong Cork Company, Lancaster, Pa., a
 corporation of Pennsylvania

Application October 31, 1945, Serial No. 625,827

9 Claims. (Cl. 259—6)

1

This invention relates to apparatus for mixing plastic materials and, in particular, to mixing apparatus adapted to handle relatively heavy, highly viscous mixes involving the application of a substantial amount of power and developing high pressure in the mix.

Mixing apparatus of various types has long been known. No mixer now available, however, has proved entirely satisfactory for handling certain classes of materials which are notoriously difficult to mix. Machines for handling asphalt-tile mixes, for example, have usually been adapted from machines originally designed for other materials and the inherent limitations thereof have prevented the processing of asphalt-tile mix with the speed and efficiency desired.

The apparatus used heretofore for heavy viscous mixes, such as that for making asphalt tile, have been subject to excessively high maintenance costs in regular operation and have required periodic reconstruction. The result of the operation of known machines, furthermore, has not been as good as desired from the standpoint of uniformity of dispersion of the various components of the mix, leaving out of consideration any question of efficiency or the time required.

I have invented a novel mixing apparatus which overcomes the above defects of previously known mixers and is characterized by further novel features and advantages which will be explained during the following detailed description of the invention. In a preferred embodiment, the apparatus of my invention comprises a mixing chamber including a pair of parallel substantially cylindrical compartments disposed side by side and in partly overlapping or intersecting relation, i. e., so that they open into each other throughout a portion of their circumference. The chamber is preferably defined by two spaced semi-cylindrical body casings, and two opposed reciprocable closures in the form of rams movable into and out of bridging position relative to the body casings. Two spaced side members define the ends of the mixing chamber, the body casings extending between the side members and being secured thereto. Shafts disposed coaxially with the cylindrical compartments are provided with stirrers or mixing blades. The rams reciprocate in guide boxes along a path normal to the plane containing the shaft axes. The upper ram has a breaker block extending into the space between the paths of the outermost portions of the stirrers. A charging opening leading into the chamber is uncovered on retraction of the upper ram. The contents of the mixing chamber fall freely

2

therefrom on retraction of the lower ram through an opening in the guide box of the latter.

A complete understanding of the invention may be had from the following detailed description in which additional novel features will be pointed out by reference to the accompanying drawings illustrating a preferred embodiment. Certain of the features disclosed herein, however, are the sole invention of Leroy Eaby and are also disclosed and claimed in his copending application Serial No. 625,791, filed October 31, 1945, for mixing apparatus.

In the drawings,

- Figure 1 is an elevation of the apparatus;
- 15. Figure 2 is a side elevation taken from the left in Figure 1 with parts in section;
- Figure 3 is a central section taken along the plane of line III—III of Figure 1;
- 20. Figure 4 is a transverse section through the upper ram taken along the plane of line IV—IV of Figure 5;
- Figure 5 is a partial section taken longitudinally through the upper ram along the plane of line V—V of Figure 3;
- 25. Figures 6 and 7 are views corresponding respectively to Figures 4 and 5, showing sections taken on line VI—VI of Fig. 7 and line VII—VII of Fig. 3; and
- Figure 8 is a partial section taken through the 30. chamber on the plane of line VIII—VIII of Figure 2 which contains the axes of the stirrer shafts.
- Referring now in detail to the drawings, the apparatus of my invention includes spaced parallel side members 10 and 11 having feet 12 adapted 35 to be bolted to a suitable foundation. Seats 13 are formed on the side plates for receiving and supporting thereon bearing pedestals 14 and 15. Stirrer shafts 16 and 17 are journaled in outboard roller bearings 18 and 19, respectively, 40 carried by the pedestals 14 and 15. The shafts 16 and 17 are parallel and lie in a plane making an angle of about 45° with the horizontal. The shafts have stirrers or blades 20 and 21 thereon. These stirrers rotate with the shafts in the mixing chamber 22.
- The mixing chamber 22 is defined by spaced upper and lower semi-cylindrical body casings 23 and 24 extending between the side members 10 and 11 and bolted thereto through flanges 25.
- 50. The remainder of the wall of the mixing chamber is constituted by an upper ram 26 and a lower ram 27, both of which are normally positioned as shown in solid lines in Figure 3 but are retractable to the positions shown in chain lines.
- 55. The ram 16 is rectangular in section, as shown in

Figure 4, and reciprocates in a guide box defined by a spacer 28 and a cooperating spacer extension 23a integral with the upper body casing 23. The spacer 28 and extension 23a are bolted to the side members 10 and 11 through marginal flanges. A charging spout 29 is formed at the lower end of the extension 23a.

The body casings 23 and 24 have pipe coils 30 and 31 cast therein for the circulation of a heating or cooling medium. The coils terminate at terminal bosses 32, 33 and 34 which are tapped for the connection of supply and return pipes, hoses or the like. The terminal bosses on the casing 24 have locations slightly different from those on the casing 23 and are designated by the same reference numeral with the suffix *a*. The upper ram 26 has a breaker block 26a on the inner end thereof projecting into the space between the paths of the tips of the wings of the stirrers 20 and 21 to improve the mixing action thereof.

The ram 26 is reciprocated in its guide box by a hydraulic piston and cylinder 35. The inner end of the cylinder is secured to a plate 36 mounted on spaced bridging channels 37 extending between the side members 10 and 11 and secured thereto by angle brackets 38. A piston rod 39 extends from the cylinder and is threaded into a central boss 40 on the upper side of the ram. A pipe coil 41 is cast in the ram and inlet and outlet connections therefor are provided by pipes 42 and 43 threaded into the ram and slidably through holes in one of two plates 44 extending between the channels 37 on opposite sides of the cylinder 35. Terminal fittings 42a and 43a afford connections for flexible conduits such as hose. The ram 26 has stop keys 45 which travel in slots 45a (see Figure 5) in the side members 10 and 11.

The lower body casing 24 is secured to a hinge bracket 47 by screws 47a extending through cooperating seating surfaces 48 and 49 on the plate and bracket. The bracket swings on a horizontal shaft 50 which passes through bearings 51 secured to the spacer 28 near the upper end thereof. When the bolts passing through the flange 25 of the casing 24 have been removed, the casing and bracket may be swung to the position shown in chain lines in Figure 3 by a fluid pressure cylinder-and-piston 52. The cylinder is trunnioned at 53 to the bracket and the piston rod is pivoted at 54 to the spacer 28. It will ordinarily not be necessary to swing the casing 24 outwardly for routine inspection and maintenance. An opening is provided in the spacer 28 near the lower end for this purpose. This opening is normally closed by a cover plate 55 hinged to the spacer 28 at 55a.

The guide box for the lower ram 27 is defined by upper and lower spacers 56 and 57 extending between the side members 10 and 11, the spacers having flanges whereby they are bolted to the side members. The lower ram, like the upper, is rectangular, and has a filler block 58 on the inner end thereof. It also has a pipe coil cast therein provided with supply and return connections similar to those described for the ram 26. The ram 27 is actuated by a cylinder-and-piston 59 mounted in the same manner as cylinder 35. The lower ram also has guide and stop keys 60 on opposite sides thereof as shown in Figure 7. These lugs travel in slots 61 in the side members 10 and 11.

Certain of the components of the mix for which the apparatus is adapted will be in a fine state of subdivision when charged into the chamber 22. In order to prevent particles of such mate-

rials from floating out through the joints between the rams 26 and 27 and the body casings 23 and 24, I provide the rams with peripheral sealing grooves 26b and 27b adjacent their inner ends. I also provide passages 23b and 23c in the body casing 23 communicating with said grooves whereby a fluid sealing medium such as grease may be delivered thereto when the rams have been moved inwardly to the positions shown in solid lines in Figure 3. The grease may be delivered by any convenient dispensing system usually including a pump, a drive therefor and suitable connections between the pump and the inlet passages.

The spacers 56 and 57 terminate short of the semi-cylindrical body casings 23 and 24. This provides a discharge opening 63 on the lower side and an access or inspection opening 64 on the upper side of the mixer.

The breaker block 26a is secured to the ram 26 by longitudinal screws 65 and transverse screws 66a passing through an outwardly extending flange 66 on each side of the block. The filler block 58 is similarly secured to the ram 27. Semi-cylindrical liners 67 are secured to the body casings 23 and 24 by screws 68 passing through outwardly extending flanges 69 (see Figure 3). The breaker and filler blocks and liners 67 preferably have an abrasion-resistant surface formed thereon.

The side members 10 and 11 are provided with removable end covers 70 and 71 overlying the ends of the chamber 22 and corresponding thereto in shape. The covers are secured to the side members by stud bolts 72 and are provided on the interior with removable liner plates 73 secured by screws 74 (see Figure 8).

Stuffing boxes 75 are formed in the covers 70 and 71 for closing the clearance between them and the shafts 16 and 17, each stuffing box being provided with a gland 76.

Each of the shafts 16 and 17 has an axial bore 78 extending thereinto from the end opposite the driving end. A pipe 79 extends through a stuffing box 80 secured to the end of each shaft. A return pipe 81 extends through the pipe 79 and into the bore 78 from a fitting 82. Suitable connections (not shown) extend from the fittings 82 to a source of heating or cooling fluid. The fittings 82 and pipes 79 and 81 remain stationary, of course, while the shafts and their stuffing boxes 80 revolve.

The stirrers 20 and 21 are keyed to the shafts 16 and 17 and the latter are preferably driven at slightly different speed in opposite directions (as indicated by the arrows in Figure 3) by a suitable motor through a conventional pinion stand. Either the upper or lower shaft may be driven at the higher speed, preferably the lower one.

It will be apparent from the foregoing that the invention provides a mixing apparatus of high efficiency compared to machines known previously, from the standpoint of the power consumed, the size of the charge, the time required for the mixing of the charge and the degree of intimacy of dispersion obtained. The apparatus is thus particularly suited for processing mixes used in the manufacture of asphalt tile but is also capable of handling other mixes such as those from which linoleum is made. The apparatus is characterized by easy and speedy charging and discharging. Ready access to all parts of the apparatus is afforded for inspection and cleaning. The apparatus requires but little maintenance even though the mixes it is intended to handle are

quite abrasive. The wearing surfaces, such as the breaker and filler blocks, the liners 67, 73 are renewable, as well as the stirrer blades themselves.

The entire mixing chamber is formed by four sections, i. e., the body casings 23 and 24 and the upper and lower rams 26 and 27, together with the end covers 10 in the side plates 10 and 11. By thus forming the mixing chamber of two semi-cylindrical casings and the two rams, the upper one having a breaker block, the machining and assembling of the parts is made easy, as well as the replacement of the wearing surfaces.

The provision of outboard bearings spaced from the side members 10 and 11 makes feasible the use of roller bearings since the clearance between the end covers and shafts is closed by stuffing boxes separate from the bearings. The mix is thus prevented from entering the bearings but the seal is readily accessible at all times. The rotating elements are independent of the end covers.

The pipe coils cast in the body plates and rams permit the temperature of the mix to be controlled as desired during various stages of the mixing operation.

Although I have illustrated and described herein but a preferred embodiment of my invention, it will be understood that changes in the construction and arrangement of parts disclosed may be made without deviating from the spirit of the invention or the scope of the appended claims.

I claim:

1. A mixer comprising a substantially closed mixing chamber including opposed substantially semi-cylindrical walls having their axes in spaced parallel and horizontal relation and in a single plane inclined to the horizontal, upper and lower closure members slidable in a path normal to said plane and forming upper and lower walls for the chamber extending between said first-mentioned walls, said lower closure member being of larger closure area than said upper closure member, side members abutting said first-mentioned walls, parallel shafts extending through said side members and mixing blades mounted on said shafts.

2. A mixer comprising a substantially closed mixing chamber including opposed substantially semi-cylindrical walls having their axes in spaced parallel and horizontal relation and in a single plane inclined to the horizontal, side members disposed at the ends of said walls, means cooperating with said members to form a guide box on the lower side of said chamber normal to said plane, and a ram slidable in said guide box in a path normal to single plane and adapted to fill the space between said side members, and between adjacent edges of said walls and, when retracted, to permit discharge of material from said chamber.

3. A mixer comprising a substantially closed mixing chamber including opposed substantially semi-cylindrical walls having their axes in spaced parallel and horizontal relation and in a single plane inclined to the horizontal, upper and lower closure members slidable in a path normal to said plane and forming upper and lower walls for the chamber extending between said first-mentioned walls, said lower closure member being reciprocal from a position in alignment with the edges of walls to a retracted position to permit the discharge of material from said chamber.

4. A mixer comprising a substantially closed mixing chamber including two parallel substantially cylindrical compartments opening into each

other along their adjacent sides and having their axes substantially parallel and horizontal and lying in a single plane inclined to the horizontal, a stirrer blade coaxially positioned in each of the 5 said compartments, upper and lower guide boxes respectively adjacent the upper and lower sides of said compartments, reciprocal rams slidable in said guide boxes in paths normal to said single plane, said rams forming portions of the upper 10 and lower walls, respectively, of said chamber, and an inlet and an outlet for the upper and lower guide boxes, respectively, said rams being respectively retractable sufficiently to permit the charging of material into the chamber through said 15 inlet and the discharging of the contents of said chamber through said outlet.

5. A mixer comprising a substantially closed mixing chamber including two parallel substantially cylindrical compartments opening into each other along their adjacent sides and having their axes substantially parallel and horizontal and lying in a single plane inclined to the horizontal, upper and lower closure members slidable in paths 20 normal to said single plane and forming upper and lower walls respectively for said chamber, reciprocal rams actuating said closure members, inner surfaces on said closure members adapted to be continuous with the remainder of the inner surfaces of said compartments when said closures 25 are in closed position.

6. A mixer comprising a substantially closed mixing chamber including two parallel substantially cylindrical compartments opening into each other along their adjacent sides and having their 30 axes substantially parallel and horizontal and lying in a single plane inclined to the horizontal, upper and lower closure members slidable in paths normal to said single plane and forming upper and lower walls for said chamber, reciprocal rams 35 actuating said closure members, inner surfaces on said closure members adapted to be continuous with the remainder of the inner surfaces of said compartments when said closures 40 are in closed position.

7. A mixer comprising a substantially closed mixing chamber, said chamber having two parallel substantially cylindrical compartments opening into each other along their adjacent sides and having their axes substantially parallel and horizontal and lying in a single plane inclined to the horizontal, a retractable ram adjacent 50 the upper sides of said compartments and adapted to operate in a direction perpendicular to said single plane, a breaker block carried on the lower end of said ram and adapted when the ram is in advanced position to constitute the 55 upper closure for said compartments, said breaker block projecting downwardly into and between said compartments, a second retractable ram adjacent the lower sides of said compartments and adapted to operate in a direction perpendicular to said single plane, a filler block carried on the upper end of said second retractable ram and adapted when the said second retractable ram is in advanced position to constitute the lower closure for said compartments, 60 said filler block having a larger closure area than said breaker block, inner surfaces on said breaker block and said filler block adapted to be substantially continuous with the remainder of the inner surfaces of said compartments, means for 65 retracting the first-mentioned retractable ram 70

to permit the charging of material to be mixed into the chamber; and means for retracting said second retractable ram to permit discharging of the contents of said chamber.

8. A mixer comprising a substantially closed mixing chamber including two parallel substantially cylindrical compartments opening into each other along their adjacent sides and having their axes substantially parallel and horizontal and lying in a single plane inclined to the horizontal, upper and lower closure members slideable in paths normal to said single plane and forming upper and lower walls respectively for said chamber, reciprocal rams actuating said closure members, removable inner wearing surfaces on said closure members adapted to be continuous with the remainder of the removable inner wearing surfaces of said compartments when said closures are in closed position, and means whereby said removable inner wearing surfaces may be replaced when sufficient wear thereof has taken place.

9. A mixer comprising a substantially closed mixing chamber, said chamber having two parallel substantially cylindrical compartments opening into each other along their adjacent sides and having their axes substantially parallel and horizontal and lying in a single plane inclined to the horizontal, upper and lower closure members for said compartments, reciprocal means

10 for actuating said closure members in a direction normal to said single plane and effecting closure when said reciprocal means are in advanced position, a sealing groove around the periphery of the closure surfaces of said closure members, and means for filling said sealing groove with a sealing medium, when said closure members are in closed position, to prevent any leakage of material being mixed in said mixing chamber.
